COMBINED DISPENSING BOTTLE AND CAP

Itaru Mita, Ashiya, Japan, assignor to Santen Pharmaceutical Manufacturing Company, Limited, Osaka, Japan

Filed Oct. 7, 1959, Ser. No. 57,843

Term of patent 14 years

(Cl. D58—8)

Fig. 1 is an elevational view of a combined dispensing bottle and cap showing my new design; Fig. 2 is a top plan view thereof; Fig. 3 is an exploded view thereof; and Fig. 4 is a cross-sectional view taken on the line 4—4 of Fig. 1.

I claim:

The ornamental design for a combined dispensing bottle and cap, as shown.
